SELF-LOCKING CONTAINER

Jesse B. Richards and William R. Van Winkle,
Marion, Ind., assignors to Indiana Fibre Products Company, Marion, Ind., a corporation

Application June 1, 1937, Serial No. 145,716

8 Claims. (Cl. 229—27)

This invention relates to a multi-cell paper board box structure which may be made of solid fibre board or corrugated paper board, as desired.

The chief object of this invention is to provide a box structure which may be shipped flat and readily assembled and secured in box formation by the user thereof without the necessity of stapling the same.

Another object of the invention is to provide, if, as and when desired, a reenforced end arrangement.

The chief feature of the invention consists in forming a box whereby the foregoing objects are accomplished.

Other objects and features of the invention will be pointed out more fully hereinafter.

The full nature of the invention will be understood from the accompanying drawing and the following description and claims:

20 In the drawing, Fig. 1 is a plan view of the main blank included in the box.

Fig. 2 is a top plan view of the box in assembled relation, the two half-covers being shown in the open position.

25 Fig. 3 is an elevational view of one of the partition members.

Fig. 4 is an elevational view of another transversely positioned partition member.

Fig. 5 is an elevational view of a reenforcing end member.

Reference will be had initially to Figs. 1 and 2 of the drawing, in which 10 indicates the box bottom forming portion, 11 the two end-forming portions hingedly connected thereto as at 12 by the score or crease. Two side portions 13 are similarly formed integral with the bottom portion 10 and hingedly connected thereto by the score or crease 14.

40 Integral with each side portion is a half-cover 15 hingedly connected to the side portion by the score or crease 16. Each half-cover has a locking flap extension 17 integral therewith and hingedly connected thereto by the score or crease 18. Each half-cover may, if desired, be provided with a finger hole 19, the purpose of which will be set forth more fully hereinafter.

45 Integral with each end portion and the upper edge thereof when in box formation is a top-forming flap 20 and hinged thereto as at 21. Each is slotted as at 22 and the width of said slot is sufficient to accommodate the thickness of the two half-cover locking flaps 17 when nested therein.

50 Integral with one side of each end portion is a flap or lateral extension designated by the num-

5 eral 23 and which is hingedly connected to the end at its side edge by the score or crease 24. One edge and the bottom associated edge of this extension is suitably relieved intermediate its ends as at 25. The upper edge of this extension is provided with a plurality of slots, the same having a predetermined spacing therebetween and the slot closest the hinge connection 24, having a predetermined spacing necessary to position said slot in predetermined position.

10 The side wall 13 immediately adjacent the extension 23 is provided with a pair of spaced slits 26 having suitable end extension 27. The length of these slits 26 is equal to the maximum width of the extension 23 remote from the score or 15 crease 28 therein. The score or crease 28 is positioned a distance from the score or crease 24 equal to the distance the slit 26 is positioned from the adjacent side edge 29 of the side portion 13.

20 To facilitate manipulation and prevent breaking of the extension, there is provided one or more creases 30 and herein two are illustrated positioned between the three slots 31 previously mentioned. It will be noted the three slots 31 are positioned equidistant from each other and 25 equidistant from the outer edge 33 of the flap 23 and from the hinge portion 28.

When these parts are arranged in box formation—see the right-hand cellular portion of Fig. 2—the portion 23 of the lateral extension between 30 the creases 24 and 28 overlaps the side wall 13 and the remainder of the extension is passed inwardly through the slit 26 and the edge 33 terminates immediately adjacent the opposite side wall 13.

35 In a similar manner but by reason of a dissimilar slit spacing, the opposite lateral extension 34 hingedly connected at 35 to the opposite side edge of each end portion 11 are provided with slots 36 having their entrances at the upper edge of the extension, the lower edge or bottom associated 40 portion being relieved as at 37. A crease 38 is positioned substantially the same distance from the union or hinge connection 35 as the similar slits 39 having the end portions 40 are positioned from the side edges 41, said slits being formed in 45 the other side wall 13.

50 The lateral extensions 34 are provided with the creased portions 42 which are positioned approximately equidistant between the three spaced slots 36. The spacing between the slots is substantially the same as the spacing between the end slot and the side edge 43 and the lateral extension or the other end slot and the crease 38. When in box formation—see the left-hand portion of Fig. 2—the portion of the lateral extension 34 between 55

the creases 38 and 35 lies parallel to the side 13 and the slotted extension portion is passed through the slit 39 and the edge 43 terminates adjacent the opposite side wall. When thus positioned, these four extensions are so arranged the slots 31 and 36 are in alignment, see Fig. 2.

The three partition members 44 shown each include upwardly directed slots 45, see Fig. 3, having a predetermined spacing and an intermediate 10 downwardly directed slot 46. The intermediate slot is centrally positioned and the other slots are arranged in pairs, the spacing between slots of each pair being substantially the same as the spacing between the pair and each side edge 47 of 15 the partition or the space between the closest slot in each pair and the central slot 46 thereof.

When the four end extensions have been properly associated with the slotted sides and thus positioned inwardly within the container, three of 20 the partitions 44 are associated therewith and interlock with these lateral extensions 23 and 34 and serve to locate the same in predetermined spaced relation to form a multiplicity of cells at each end of the container.

25 Another partition member 48 is provided on its bottom edge with three upwardly directed slots 49. This is the central partition member and when associated with the partitions 44, said partition 48 is seated in the central slots 46 in the 30 top edge of the partitions 44, thereby providing therewith and the extensions 34, an intermediate group of cells. It will be apparent that the length of the partition 44 shown in Fig. 3 is substantially the length of the box and the length of the partition 48 shown in Fig. 4 is substantially 35 the width of the box.

When all the extensions are properly positioned and the several partitions are properly associated therewith and with each other, it will be apparent that an interlocking relationship is 40 obtained whereby the respective partitions prevent the accidental disassembling or disassociation of the box portions from box-forming relation. When articles such as ketchup, beer, Coca Cola, or the like, bottles are packed in the container, one to a cell, the two end extensions 20 are turned inwardly, then the two half-covers are turned inwardly and the two flap extensions 17 thereon are caused to nest at their opposite ends in the slots 22 of the end extensions 20. The container is then in closed relation and the covers are retained in that position through frictional engagement with each other and with the side edges of the slots 20.

50 To facilitate ready opening of one or both half-covers, the finger hole or holes 18, may be provided.

It will be apparent that in place of extensions 20 and half-covers 15, there may be employed a 55 single cover portion integral with either side 13 and provided with rim-forming extensions which can be interlocked together at adjacent corners and thus provide a single full cover box, all without the use of staples to secure the parts when assembled in box formation.

With such an arrangement, the extensions 20 may be used, if desired, but there would be no necessity for slots 22 to be therein.

It will be observed that end extensions 23 have 70 a conformation between creases 24 and 28, indicated by the numeral 58, which is different from the conformation indicated by the numeral 51 of the lateral extension 34 between creases 35 and 38. The side 13 which is associated with the lateral extensions 23 thus has a greater por-

tion of the side exposed and the lesser portion overlapped by the extensions. The other side has a greater amount overlapped by the lateral extension 34 and a lesser amount exposed. This permits a larger available printing area on one side 13 than the other. If desired, either type of conformation 50 or 51 may be used in all extensions to the exclusion of the other form.

The foregoing constitutes a description of a container suitable for the general purpose described and the container of the simplest form, it being noted that each end portion is provided with a hand-hole slot or opening 52.

When it is desired to form a slightly stronger box and particularly when hand-holes are provided so that the end walls provided with said openings will not be deformed when the box is handled with its contents, each end may be reinforced by a member 54 of substantially the same area as the end 11. The end insert will be 20 provided with a registering hand-hole 55 and the two end members 11 and 54 are suitably "stitched" together with metal members, conventional to the industry and by the box manufacturer, and the positioning thereof is indicated by the dotted lines in Figs. 1 and 5 and by the numerals 56 and 57, respectively. The reenforcing end preferably is positioned adjacent the inside face of the end portion of the main blank.

In order to reduce the overall width of the 30 blank shown in Fig. 1 whenever desired, the end flap 20 with its slot 22 may be formed integral with the end reenforcing member 54 and in that event the end flap extensions 20 are not provided on the ends 11. It will be noted, however, 35 in the form illustrated, see Fig. 2, that the end flaps 20 when turned inwardly bear upon the upper edge 59 of the end reenforcing member 54 and thus serve to a certain extent to prevent inward movement or depression of the top-forming flaps 20 which in turn serve to a suitable degree 40 to maintain the half-covers in coplanar relationship rather than in a downwardly inclined relationship.

While the invention has been described in 45 great detail in the foregoing specification and similarly illustrated in the drawing, the same is to be considered illustrative and not restrictive in character. The various modifications herein illustrated and/or described as well as others 50 which will readily suggest themselves to persons skilled in this art, are all considered to be within the broad scope of this invention, reference being had to the appended claims.

The invention claimed is:—

1. In a self-locking paper board box, the combination of a bottom, two opposite sides each having a pair of slits therein, the slits in opposite sides being other than in alignment, two intermediate sides, and lateral extensions from each side edge of the intermediate sides initially transverse thereto and each extending through a first-mentioned side slit and terminating immediately adjacent the inner face of the side opposite the immediate extension-intersected side, the portions of the extensions beyond the intersections constituting partitions.

2. A box as defined by claim 1, characterized by each extension beyond the intersection portion including a slot, the slots being in registration, and by the addition of a transverse partition interlockingly associated with the slotted intersecting portions at the slots.

3. A box as defined by claim 1, characterized by each extension beyond the intersection portion.

including a plurality of spaced slots, slots in adjacent extended portions being in registration, and by the addition of a plurality of transverse partitions interlockingly associated with the extended portions at the slots thereof.

5 4. A box as defined by claim 1, characterized by each extension beyond the intersection portion including a slot, the slots being in registration, and by the addition of a transverse partition interlockingly associated with the slotted intersecting portions at the slots, and another partition of a length substantially that of the extended portions and positioned parallel thereto and interlockingly associated with the transverse partition.

10 5. A box as defined by claim 1, characterized by each extension beyond the intersection portion including a plurality of spaced slots, slots in adjacent extended portions being in registration, and by the addition of a plurality of transverse partitions, interlockingly associated with the extended portions at the slots thereof, and another

partition of a length substantially that of the extended portions and positioned parallel thereto and interlockingly associated with the transverse partitions.

6. A device as defined by claim 1, characterized by the slits in one side being positioned at a distance approximately one-sixth the length of that side from the side edges thereof.

10 7. A device as defined by claim 1, characterized by the slits in one side being positioned at a distance approximately one-third the length of that side from the adjacent side edges thereof.

15 8. A device as defined by claim 1, characterized by the slits in one side being positioned at a distance approximately one-sixth the length of that side from the side edges thereof, the slits in the opposite side being positioned at a distance one-third the side length from the adjacent side edges thereof.
